UNITED STATES PATENT OFFICE.

HERBERT COE AND CHARLES P. LAWRENCE, OF NEW YORK, N. Y.

IDENTIFICATION DEVICE.

1,320,448.

Specification of Letters Patent.

Patented Nov. 4, 1919.

Application filed May 26, 1919. Serial No. 299,785.

To all whom it may concern:

Be it known that we, HERBERT COE and CHARLES P. LAWRENCE, both citizens of the United States, and residents of the city of New York, in the county of Kings and State of New York, have invented a certain new and useful Identification Device, of which the following is a specification.

This invention relates to identification devices.

Heretofore, a large amount of inconveniences, delays and losses have been experienced, in the shipment of goods, baggage, or other articles, through the accidental destruction, loss or effacement of the tag, label, or other means bearing the recipient's or consignee's name and address and other such data.

The principal object of our invention is to remedy the above mentioned difficulties and disadvantages, and to provide simple, economical, conveniently utilizable, and improved means wherewith the shipper will be enabled to ascertain the data concerning the addressee, in case of any accidental loss or effacement of the regular address.

Other objects and advantages will herein-after appear.

The accompanying drawing shows a cross-sectional plan view of the identification device.

The identification device is adapted for trunks, hand baggage, and similar articles. In the case of such articles, the wall 7 thereof, which we will assume to be that of a trunk, is provided with a circular opening 8, in which there is fitted a circular wall 9 extending from a metal flange 10, which is secured to the wall 7 on the inner side of the trunk by the rivets 11 and is provided with a tapped hub 12 the center line of which coincides with that of the wall 9. A short metal tube 13, which is closed at one end by a plate 14 secured thereto, is fastened to the hub 12 and extends into the interior of the trunk. Access may be thus gained to the interior of tube 13 through the opening 8 lined by the wall 9 and the tapped opening 15 of the hub 12, and the tube 13 may be closed by a plug 16 which threads into the opening 15.

When it is desired to forward the trunk or similar article, it may be properly marked with the proper name and address by any usual means, such as a pasteur, and then a slip of paper, bearing the addressee's name and

address, may be inserted into the tube 13 and the plug 16 threaded in place into the hub 12. The slip of paper bearing the address will now remain concealed within the tube 13 and thoroughly protected therewith, until such time as the regular exposed address should become effaced from some accidental cause, whereupon the plug 16 may be removed, by applying a screw-driver to the notched projection 17 thereof, and the paper slip may be then removed from the tube 13 and read to ascertain the particulars regarding the addressee. The carrier may then remark the trunk, replace the paper slip within the tube 13 and close it with the plug 16, and send off the trunk to its proper destination. The face of the wall 8 may have marked thereon the inscription "In case address is lost remove this plate." It will be evident that this device will not in any way detract from the neatness of appearance or flushness of the trunk or other article, inasmuch as the structure is entirely on the interior side of the trunk wall, and the only visible parts on the exterior are the wall 9 and the plug 16 therewithin.

Variations may be resorted to within the scope of the invention.

Having thus described our invention, we claim:

1. A device for identifying receptacles in transit having the combination of means for containing an address-bearing element located on the inside side of the wall of the receptacle and being secured thereto, the receptacle having an opening extending therethrough for gaining access into said means, and removable means for closing said means at said opening and concealing said address-bearing element.

2. A device for identifying receptacles in transit having the combination of a tube for containing an address-bearing element located on the inside side of the wall of the receptacle and being secured thereto, the receptacle having an opening extending therethrough for gaining access into said tube, and a removable plug for closing said tube through said opening and concealing said address-bearing element within the tube.

3. A device for identifying receptacles in transit having the combination of a tube for containing an address-bearing element located on the inside side of the wall of the receptacle and projecting therefrom, a flange located in the interior of the receptacle and

secured to the wall thereof, said tube being closed at one end and having its other end secured to said flange, said flange having a tapped opening leading to the interior of said tube, the wall of said receptacle having an opening extending therethrough leading to said tapped opening, and a threaded plug for closing said tube threading into said

tapped opening through the opening in the receptacle and concealing said address-bearing element within the tube.

Signed at the city of New York, in the county of New York, and State of New York, this 23rd day of May, A. D. 1919.

HERBERT COE.

CHARLES P. LAWRENCE.
